UNITED STATES PATENT OFFICE.

GEORGE B. KOONS, OF HALFMONB BAY, CALIFORNIA.

PIPE-TONGS.

SPECIFICATION forming part of Letters Patent No. 321,038, dated June 30, 1885.

Application filed March 16, 1885. (No model.)

To all whom it may concern:

Be it known that I, GEORGE B. KOONS, of 5
Halfmoon Bay, San Mateo county, State of
California, have invented an Improvement in
Pipe-Tongs; and I hereby declare the follow-
ing to be a full, clear, and exact description
of the same.

My invention relates to an improved pipe-
tongs. It consists of a lever-bar having the
outer end slightly curved beyond the fulcrum-
pin, which passes through it, a hook-shaped
jaw hinged to the fulcrum-pin so that its ends
will pass by and overlap the curved end or
jaw of the lever to which it is hinged, the in-
terior of both the shaft and the movable jaw
being corrugated or toothed, so that they will
hold the pipe.

Referring to the accompanying drawings
for a more complete explanation of my inven-
tion, Figure 1 is a view of my device showing
the jaws open. Fig. 2 shows the jaws closed
upon a pipe or tube.

A is a handle or lever of sufficient length,
having the opposite end curved to one side,
25 as shown at B. This lever is flattened at C,
and the hook-shaped jaw D is pivoted or ful-
crumed to this flat portion of the lever by a
bolt, E. The portion B, forming the jaw upon
the main lever, is made of such thickness that
30 it extends outward, so as to stand opposite
the jaw D upon the side, where it is bolted to
the lever, and the opposite hinged jaw, D,
in like manner extends over the side of the

portion C, to which it is fulcrumed, so as to
give considerable thickness and bring the two 35
jaws opposite to each other. The jaw D is
made of such a length and bent to such an an-
gle that its outer end will just pass the point
of the jaw B when the two are closed together,
and by this construction the two jaws will take 40
in pipes having a considerable difference in di-
ameter. The interior of both jaws is toothed
or corrugated, so as to take hold of the pipe,
and it will be seen from the peculiar shape of
the jaw B that the pressure will be applied 45
to three sides of the pipe or bolt upon which
the device is to act. This enables me to ap-
ply a very strong power without danger of in-
denting or crushing the pipe.

Having thus described my invention, what I 50
claim as new, and desire to secure by Letters
Patent, is—

In a pipe-tongs, a lever-arm having its outer
end curved to form a hooked jaw having a
concave gripping-surface, in combination with 55
a hinged movable hook-shaped jaw pivoted to
the lever and having its toothed portion over-
lapping the lever so as to stand opposite the
fixed jaw, substantially as herein described.

In witness whereof I have hereunto set my 50
hand.

GEORGE B. KOONS.
